UNITED STATES PATENT OFFICE

THOMAS F. CONNORS, OF COLUMBUS, OHIO, ASSIGNOR, BY MESNE ASSIGNMENTS, TO CHARLES G. MCGHIE, OF ST. CATHARINES, ONTARIO, CANADA

TOOL

Application filed July 1, 1927. Serial No. 202,840.

This invention in its broader aspects relates to tools and other devices having handles to be gripped by the user, and in some of its aspects the invention has to do particularly with such load bearing tools as hoes, rakes, shovels, forks and the like.

One of the objects of the invention is the provision of a tool or other handled device having a handle of improved construction.

10. Further objects of the invention are comprised in the provision of an improved load bearing tool having an elongated handle and which is exceedingly strong and durable, of very moderate weight, well balanced in the 15 hands of the user, and the handle as well as the body or tool proper of which is made of material which is always readily available in suitable quality at moderate prices.

Other objects more or less incidental or 20 ancillary to the foregoing will be apparent to those skilled in the art from an examination of the following description in connection with the accompanying drawing.

In the drawing:

25. Fig. 1 is a side elevation showing one form of my improved load bearing tool, some parts being broken away and others in section to illustrate the detail construction.

Fig. 2 is a sectional view taken on the line 30 2-2 of Fig. 1 looking in the direction indicated by the arrows and illustrating the manner of attaching the shank to the tool proper.

Fig. 3 is a perspective view showing the attaching shank.

35. Fig. 4 is an enlarged fragmentary sectional view of the handle illustrating the manner of securing the heat insulating covering.

Fig. 5 is an enlarged fragmentary sectional view showing the manner of securing the 40 grip member to the upper end of the handle.

Fig. 6 is an enlarged fragmentary sectional view illustrating the manner of securing the metal ferrule to the lower portion of the handle.

45. Fig. 7 is an enlarged elevation showing a section of the handle with the heat-insulating material removed.

Fig. 8 is a view similar to Fig. 1 showing the manner of attaching a tubular steel handle to a different type of tool.

Fig. 9 is an enlarged fragmentary sectional view illustrating a modified construction of the upper end of the handle.

Fig. 10 is an enlarged fragmentary sectional view showing a modified wrapping 55 material for the handle.

Referring first to the construction illustrated in Figs. 1 to 7, inclusive, my improved load bearing tool comprises a tool proper which in this instance is in the form of a hoe 60 blade 1, a tubular metallic handle 2, a solid metal shank 3 connecting the handle and tool proper, and a wooden grip member 4 secured to the upper end of the handle 2.

The tubular metal handle 2 comprises an 65 elongated cylindrical body portion or shaft section 5 and a reduced extension 6 formed integral with the shaft section. One end of the shank 3 fits within the open end of the reduced extension 6 and is welded thereto at 70

7. The shank 3 is in the shape of a goose neck and is provided at its free end with an integral enlargement 8 having a flat surface 9 which lies against the front face of the hoe blade 1. See Figs. 1, 2 and 3. The enlargement 8 is rigidly secured to the hoe blade by means of spot welding indicated at 10, 10. A V-shaped notch 11 is cut in the upper edge 75 of the blade and receives a correspondingly V-shaped projection 12 formed on the rear 80 of the shank 3 thus providing a means for centering the shank and hoe blade during the spot welding.

Due to the heat absorbing qualities and 85 high thermal conductivity of metal it is necessary, in the case of tools exposed to the hot sun of summer, in order to have a comfortable gripping surface for the hands of the user, to cover a part of the handle with some suitable heat-insulating material. A 90 fibrous or cellular substance is desirable for this purpose. For example, I have found that cork is a very suitable material particularly when prepared in the form of what I term composition cork, which consists of 95 powdered or granular cork mixed with adhesive and rolled into sheets, either with or without a backing of woven fabric. Such sheet material can be given a suitably smooth calendered surface, is flexible and, especially 100

if a fabric backing is employed, has a high tensile strength. For the sake of simplicity and convenience, I will use the term "composition cork" herein as inclusive of any composite sheet material including cork or an equivalent fibrous or cellular non-conductor as the principle non-conducting constituent and affording a surface suitable for the handle of a tool or the like.

5 In the preferred form of tool handle illustrated, the cylindrical body portion 5 of the handle is covered with a layer of composition cork 13 which is in the form of a relatively thin ribbon-like strip 14 wound spirally upon the exterior surface of the cylindrical body portion with the adjacent edges of neighboring convolutions of the cork arranged in abutting relation to each other. See Fig. 4. The strip 14 is firmly secured to 10 the surface of the handle by means of a water-proof cement indicated at 15, which is applied to the strip as it is being wound upon the handle. The exterior surface of the cylindrical body portion is roughened, 15 preferably by knurling, as indicated at 16 in Fig. 7 so as to provide a roughened surface to which the water-proof cement will firmly adhere. The cement is applied in quantities slightly in excess of what would ordinarily 20 be required so that it will flow into and fill the space between the abutting edges of the cork and thus seal and integrate the whole after it has dried. The covered handle is treated with sand paper or the like to remove 25 any excess cement, thus producing a handle surface that is heat insulated, smooth and otherwise suitable for the intended use.

As previously stated the composition cork may or may not have a fabric backing. As 30 shown in Fig. 4 it does not have such a backing while in the construction illustrated in Fig. 10, the sheet comprises a fabric back 17 to which is strongly secured the coating of cork and adhesive. In making the fabric-backed sheet, the adhesive is caused to flow upon and spread over the web of cloth as the latter is advanced. The powdered cork, or equivalent material, is then delivered upon and uniformly spread over the web which 35 then passes between rollers that compress and integrate the fabric, adhesive and cork and give the latter a suitably smooth surface for the intended use.

50 A metal ferrule 19 fits over the lower end of the spirally wrapped cork of the handle so as to protect the same. The ferrule is firmly secured to the handle at the juncture of the cylindrical body portion 5 and reduced extension 6 by any suitable means such as 55 prick punching indicated at 20 in Fig. 6.

The upper end of the handle is fitted with a grip member 4 somewhat larger in diameter than the shaft of the handle. This member is made of suitable hardwood and comprises 60 a gripping portion 21 which is of sufficient

length to accommodate the hand of the workman, an extension 22 which is driven into the open end of the cylindrical body portion 5, and a part 23 which fits over and surrounds the outer end of the composition cork wrapping and serves as a means for protecting the cork as in the case of the metal ferrule. The grip member is firmly secured within the free end of the cylindrical body portion by any suitable means such as prick punching as indicated at 24. The extension 22 serves as a reenforcing means for the end of the tubular handle.

70 My improved tool is manufactured and assembled in the following manner. In forming the handle of the tool I take a suitable length of drawn or welded steel tubing of circular cross section and uniform diameter throughout. First, one end of this tube is swaged to provide the reduced or tapered 75 extension 6. The tube then has the cylindrical part of its surface mechanically roughened in some suitable manner, as by means of a knurling tool, sand blast, wire brush or the like. I prefer to accomplish the roughening by knurling and this can be effected rapidly by a suitable machine in which the knurling wheel or wheels and the tube are simultaneously rotated and fed axially relative to each other, so that the knurling wheel follows a spiral path on the surface of the tube as indicated in Fig. 7. Next the covering of heat-insulating cork is applied to the handle tube. This is preferably accomplished by a special mechanism such as is 80 disclosed in the copending application of Perry Okey, Serial No. 169,617, filed February 19, 1927. The metal ferrule is placed over 85 the lower end of the cork wrapping and is secured to the handle by prick punching. The grip member 4 is then secured in position within the free end of the cylindrical body portion and the handle put in a rack to permit the cement to set and thoroughly dry, 90 after which the handle is sanded to remove surplus cement. The shank having been previously welded to the hoe blade is then secured at its free end to the reduced extension of the handle by welding.

95 In the construction illustrated in Fig. 9 I have substituted for the grip member of the prior construction a comparatively short finishing plug 30. This plug comprises a short body portion 31 which fits over the end of the handle 2, an overlapping portion 32 which protects the end of the composition cork covering, and an extension 33 which fits within and reenforces the end of the tubular handle. As in the prior construction, the plug 30 is firmly secured to the handle by 100 punching indicated at 34. The plug 30 may be used as a finishing means for the outer end of the handle where the longer wooden grip of the prior construction is not desired.

105 In the construction illustrated in Fig. 8

I have illustrated a modified manner of attaching a tubular metallic handle to a load bearing tool. In this construction I provide, as before, a tubular metallic handle 40 comprising a cylindrical body portion 41, a reduced extension 42 formed integrally with the body portion, and a hardwood grip member 43 fitting within and finishing the outer end of the tubular handle. The body portion is covered with a ribbon-like strip of composition cork 44 spirally wound upon and cemented to the knurled exterior surface thereof. A ferrule 45 and an overlapping part 46 of the grip member serve to protect the ends of the cork wrapping.

In this construction I provide a tapered hardwood plug 47 which fits within the reduced extension 42 of the tubular handle. The plug is provided with a longitudinally arranged opening 48 which receives a shank 49 formed integral with a tool proper which in this instance is in the form of a fork 50. The shank 49 is secured within the opening 48 in the hardwood plug 47 by means of a rivet 51. It is to be noted that the rivet 51 extends through the extension 42, plug 47 and shank 49 and thereby serves to also secure the plug 47 to the reduced extension.

A second rivet 52 is provided as an additional means for securing the plug within the extension 42. A metal cap 53 tightly fits over the inner end of the plug 47, and serves to prevent the plug from splitting both during manufacture and subsequent use of the tool. The rivet 52 extends through the reduced extension 42, the sides of the metal cap 53 and the hardwood plug, and when secured in place will force the side portions of the cap into the sides of the wooden plug and thus firmly secure the same to the reduced extension of the handle. The rivets 51 and 52 are arranged in planes extending at right angles to each other to provide a rigid fastening means for the plug, and also to aid in preventing the plug from splitting, as will be readily understood.

Heretofore such load bearing tools as hoes, rakes, shovels and the like have been provided with handles formed from some suitable wood such as ash or hickory, though little of the latter wood is now available. Handles of this character have a number of disadvantages such as the flexing or bending of the handle under the weight of a load, or pressure during use; the breaking of the handle under excess loads or pressures; and the troublesome coming apart of the handle and the tool which is due to the ineffective known methods of securing a wooden handle to a metal tool proper. Also, due to the growing scarcity of even suitable ash timber, manufacturers have been forced to place handles of inferior grades in the tools with the result that the handles are more easily broken and have to be replaced a greater

number of times during the life of the tool proper.

An important feature of my improved handle construction resides in the fact that the portion thereof covered by the heat-insulating wrapping throughout its length is of uniform circular cross section. For this reason it is possible to effect the helical wrapping with the ribbon of composition cork without subjecting the latter to the uneven stresses and strains that would occur if the ribbon were snugly wrapped on a shaft of varying diameter. Furthermore if the shaft were of varying diameter the angle at which the ribbon is fed to the shaft would have to correspondingly vary and this would practically necessitate the wrapping of the ribbon by hand and at a cost that would be prohibitive for most purposes. With my construction it is possible to effect the wrapping by comparatively simple mechanical means and at low cost.

In providing my tool with a tubular metallic handle which is integrally united with the tool proper, I produce an unusually strong and durable construction which is made from materials which are always obtainable in suitable quantity and at moderate prices. The tool is well-balanced in the hands of the user, and the handle will not bend or break during the most strenuous use. The composition cork covering provides in addition to an effective heat-insulated gripping surface, one that is slightly yielding and smooth and as a result can be effectively grasped with a minimum tendency to blister the hands of the workman during use. The metal ferrule and the overlapping portions of both the grip member and the finishing plug provide an effective means for protecting the ends of the cork strip.

Both the plug and the grip member provide a neat finish for the upper end of the handle, and in addition the extensions provide an effective means for securing the plug to the handle and also serve to strengthen the end of the handle.

The specific means for securing the tool proper to the handle shown in Fig. 8 is not claimed herein as it constitutes the subject matter of my copending application Serial No. 202,839, filed July 1, 1927.

In the following claims, the term "tool" is to be given the broad meaning of an operating head for an implement, and it will be understood that the term would embrace the heads of golf clubs, the head of a rake, fork, hoe, the flexible portion of a fishing rod or the like, the term being a generic term.

As previously indicated various modifications of the device as herein disclosed can be made without departing from the invention, the scope of which is indicated by the appended claims.

What I claim is:

1. In a load bearing tool, the combination of a tool proper; a metallic shank integrally united at one of its ends with the tool proper; a tubular metallic handle having one of its ends integrally united with the other end of the said shank and comprising an elongated body portion knurled on its exterior surface; a heat insulating strip of composition cork spirally wound upon and cemented to the knurled surface of the said body portion; and a grip member secured to the free end of the said body portion and having a portion thereof overlying the end of the cork covering for protecting the same.
- 15 2. A tool handle comprising in combination an elongated straight tubular metallic shaft section of uniform diameter; a heat-insulating strip of composition cork spirally wound upon and cemented to the said shaft section; an extension formed integral with one end of the said shaft section for the attachment of a tool; a ferrule secured to the said handle adjacent the juncture of the shaft section and integral extension and having a portion thereof overlying one end of the cork covering; and a member secured to the free end of the said shaft section and having a portion thereof overlying the other end of the cork covering.
- 25 3. A tool handle comprising in combination an elongated straight metallic tubular portion having a roughened exterior surface of substantially circular cross section; a heat insulating strip of composition cork spirally wound on the said tubular portion, these adhesive means rigidly securing the cork to said roughened surface; and a non-wound extension formed integral with one end of the said tubular portion for the attachment of a tool.
- 35 40 4. A handle comprising in combination, an elongated substantially straight metallic tubular portion of substantially circular cross section, an insulating strip of composition cork material, spirally wound on said tubular portion and rigidly secured thereto, a hand grip secured to the free end of said tubular portion and comprising a tubular flange telescoped over the end portion of said wound strip, means restraining longitudinal movement of said hand grip on said tubular portion, and means for rigidly securing an operating head to the other end of the said tubular portion.
- 45 50 55 5. In testimony whereof, I hereunto affix my signature.

THOMAS F. CONNORS.
